UNITED STATES PATENT OFFICE.

WILLIAM B. GETTY, OF HICKSVILLE, OHIO.

ROAD-CART.

SPECIFICATION forming part of Letters Patent No. 349,882, dated September 28, 1886.

Application filed August 4, 1886. Serial No. 210,034. (No model.)

To all whom it may concern:

Be it known that I, WILLIAM B. GETTY, a citizen of the United States, residing at Hicksville, in the county of Defiance and State of Ohio, have invented a new and useful Improvement in Road-Carts, of which the following is a specification.

My invention relates to improvements in road-carts; and it consists of the peculiar combination and novel construction and arrangement of the various parts for service, substantially as hereinafter fully set forth, and particularly pointed out in the claims.

The object of my invention is to provide a road-cart with an improved seat-frame which shall be so suspended and arranged that the objectionable motion given to the thills or shafts by the draft-animal in this class of vehicles, and which is known as the "horse motion," shall be effectually overcome, whereby a comfortable and easy motion will be given to the occupant of the vehicle.

A further object of my invention is to provide an improved seat-frame and suspending devices therefor, which shall be very simple and strong in construction, not liable to get out of order or disarranged, and cheap and inexpensive of manufacture.

In the accompanying drawings, which illustrate a road-cart embodying my invention, Figure 1 is a side elevation with the carrying-wheels removed. Fig. 2 is a top plan view corresponding to Fig. 1. Fig. 3 is a rear elevation. Fig. 4 is a detached perspective view of the seat-frame, and Fig. 5 is a like view of the rear spring and the suspending devices for the seat-frame. Fig. 6 is a longitudinal vertical sectional view on the line $\alpha\alpha$ of Fig. 2.

Referring to the drawings, in which like letters of reference denote corresponding parts in all the figures, A designates the axle of my improved road-cart, which is preferably bent upwardly at its middle so that the middle portion thereof is out of line with the ends, and B the shafts or thills, which extend rearwardly to the axle, and are rigidly connected thereto by means of the clips b, which embrace the axle and the rear ends of the thills, as clearly shown. The thills are curved downwardly at their rear ends, as at b', and the thills are thus elevated at their front ends into a higher posi-

tion than at their rear ends, so that the lower portion of the seat-suspending frame C is located beneath the plane of the front or higher ends of the thills, which are connected and braced by a cross-bar, B', to which is pivotally connected the single-tree B², as is usual in this class of devices.

The seat carrying or suspending frame C preferably consists of the side rails or bars, C', which are inclined or arranged diagonally with relation to each other and bent upwardly at their front ends in curved lines, as at c, the upright or vertical standards C², and the transverse rails or bars C³, which connect the side rails, C', at or near the rear ends thereof, so as to provide a platform or support for the feet of the driver or occupant of the vehicle. These rails or bars C³, that form the support or platform for the feet, are secured to the side rails, C', in any suitable or preferred manner for strength and stability, and the front or foremost of the said rails is curved longitudinally, so as to assume substantially the form of a bow or segment, the ends thereof being rigidly affixed to the seat carrying or supporting frame, as described, while at its middle the said segmental bar or rail is provided with a slot or mortise, c', in which the rail or bar immediately in rear thereof is fitted to strengthen the platform or support. This platform or support is provided with two stirrups or stops, D, which are each bent from a single piece of metal to form an open loop, and is affixed to the segmental-shaped rail or bar of the platform and the side rails, C', one of the loop-shaped stirrups being arranged on each side of the platform or support of the seat-carrying frame C.

The vertically-disposed standards C² of the seat-carrying frame C are arranged at the rear ends of the latter and in a slightly-inclined position, the said standards being preferably formed in a single piece with the side rails, C', of the frame C, and at its upper end each of the standards is provided with a horizontal arm or bar, e, which extends or projects rearwardly from the standard, and to which the seat E is rigidly affixed in any suitable or preferred manner, the seat being of any approved pattern. The said rails C' of the seat-carrying frame and the vertical standards or

uprights thereof are braced and strengthened by means of diagonal rods or bars F, the rear ends of which are rigidly affixed to the standards, and the front ends thereof are likewise secured to the bent or curved ends e of the said rails, the said front ends of the rods or bars being bent or inclined upwardly to form the angular arms f, which are provided at their free ends with spaced lugs f', which are disposed in vertical lines at the extreme free ends of the side rails, C, of the seat carrying or supporting frame, the function of these spaced vertical lugs being hereinafter explained.

The vertical standards or uprights C² C² of the seat-carrying frame are each provided with brace-irons G, which are rigidly secured to the same on their inner sides, and the lower ends of these brace-irons are inclined or curved rearwardly to form the arms g, which extend or project beyond the vertical faces of the standards, and to the free ends of the extended arms g of the brace-irons are pivotally connected the lower ends of vertically-disposed links or shackles H by means of a suitable pivot pin or bolt. The upper ends of these shackles or links are pivotally connected to the free ends of a spring-support, I, which is disposed in a vertical position immediately beneath the seat, and thereby partially protected and concealed from view. The ends of this support I are curved or bent upwardly and then downwardly, so as to assume the shape of hooks, to the free ends of which the shackles are pivotally connected, as hereinbefore described; but this shape or form of the ends of the support can be varied without departing from the principle of my invention.

The support I is rigidly affixed in any suitable manner, and at its middle to a block, J, which in turn is secured to a spring, K, which is arranged transversely across the vehicle and extends from one shaft to the other thereof. This spring K is arranged in close proximity to the axle, and it lies on a plane beneath the axle, said spring being arranged in front of the axle and in rear of the seat carrying or supporting frame C. The ends of this spring K are bent or curved over upon themselves, as at k, and the free bent ends of the spring are pivotally connected to the thills at the rear ends thereof by means of a pin or bolt which passes through aligned openings in vertical lugs at the rear of the thills, although this form of pivot-connection of the spring with the thills can be varied. This spring K serves as the support for the rear end of the seat and its carrying-frame, and the front end of the said frame is suspended beneath the thills and out of contact therewith by means of curved springs L, which are rigidly secured to the thills at one end, and pivotally connected at their other ends with the vertical lugs f' at the front of the side rails, C, of the said seat frame. The springs L are each formed of a single piece of elastic or resilient metal, and they are arranged beneath and in line with the thills, so as to be concealed and protected by the thills

partially. The seat-carrying frame C is thus suspended beneath the axle and the thills and entirely out of contact with the said parts by resilient and yielding supporting devices, whereby the objectionable jogging motion that is imparted to the thills and the axle, and which is known to the art by the name of "horse motion," is entirely overcome, the seat being given an easy and agreeable motion, which is much sought after in this class of devices. The seat-carrying frame is suspended beneath the thills, so that the seat, which occupies an elevated position on the frame, is substantially on the same line or plane as the front elevated portion of the thills, which is sufficient to permit the driver to see his way in driving and guiding the animal.

The rear curved ends of the thills are braced and strengthened by means of rods or bars M, which are rigidly affixed at their front ends to the elevated or higher portions of the thills, and the rear ends are secured to the lower portion of the thills at or near the point of connection of the thills with the axle.

N designates a hanger, which depends from the axle at one side thereof, and to the lower ends of the hanger is secured a step, n, by means of which the occupant of the vehicle can very readily alight or enter the vehicle.

The seat-carrying frame is very light, simple, and strong in construction, and the connections intermediate of the said frame and the thills and axle are also very simple, strong, and of sufficient elasticity to insure an easy and resilient motion to the seat.

To further insure an easy motion to the seat and its frame the support I is also made of spring or elastic metal, which will yield and give to the motions of the frame.

The device is very light and simple in construction, and can be manufactured for a comparatively small sum.

Slight changes in the form and proportion of parts can be made without departing from the spirit or sacrificing the advantages of my invention.

Having thus fully described my invention, what I claim as new, and desire to secure by Letters Patent, is—

1. In a road-cart, the combination of an axle, the thills connected to the axle, a suspended frame arranged between the thills and axle and beneath the plane thereof and carrying an elevated seat, the front springs affixed to the thills and pivotally connected to the front part of the suspended frame, a transverse rear spring arranged in front of the axle and connected at its ends with the rear ends of the thills, a spring-support secured to the middle of the spring, and the vertical shackles pivotally connected to the suspended frame and the free ends of the spring-support, substantially as described, for the purpose set forth.

2. In a road-cart, the combination of an axle, the thills connected to the axle, a sus-

pended frame arranged between the thills and axle and beneath the plane thereof and carrying an elevated seat, the curved front springs affixed rigidly to the thills at one end and pivotally connected to the front end of the suspended frame, a transverse spring arranged in front of the axle and having its extremities bent around the rear ends of the thills and pivotally connected thereto, a spring-support secured to the middle of the transverse spring, and the vertically-disposed shackles pivotally connected to the suspended frame and the free ends of the spring-support, substantially as described, for the purpose set forth.

15 3. The combination, in a road-cart, of the thills, an axle, a frame carrying a seat, the front springs connecting the frame with the thills, the rear transverse spring, the block secured to the transverse spring at its middle, 20 the spring-support affixed to the block and having the curved ends, the brace-irons affixed to the seat-frame, and the pivoted vertical shackles intermediate of the free ends of the spring-support and the brace-irons, substantially as described.

25 4. In a road-cart, the combination of an axle, the thills connected with the axle, a frame carrying a seat and comprising the side rails, the platform-bars connecting the side

rails and the uprights on which the seat is secured, and the rear and front springs, K L, arranged and connected, as described, for suspending the frame out of contact with the thills and axle, substantially as described.

5. In a road-cart, the combination of an 35 axle, the thills connected thereto, a suspended frame comprising the diagonal side rails or bars having the upwardly-curved front ends, the transverse rails or bars connecting the side rails near their rear ends, a segmental 40 cross-bar having a mortise in its rear side in which one edge of one of the transverse bars is fitted, and the vertically-disposed standards affixed to the rear ends of the side bars and carrying a seat at their upper ends, and 45 the front and rear springs arranged, as described, for suspending the frame from the axle and thills and out of contact therewith, substantially as described, for the purpose set forth.

50 In testimony that I claim the foregoing as my own I have hereto affixed my signature in presence of two witnesses.

WILLIAM B. GETTY.
